CLAIM

I claim the ornamental design for an axis rongeur, as shown and described.

DESCRIPTION

FIG. 1 is a perspective view of the axis rongeur;

FIG. 2 is a left side view thereof;

FIG. 3 is a right side view thereof;

FIG. 4 is a front side view thereof;

FIG. 5 is a rear side view thereof;

FIG. 6 is a top side view thereof; and,

FIG. 7 is a bottom side view thereof.
